WALKING FIGURINE

Robert Ellis, 3355 Country Club Road, Bronx 65, N.Y.

Filed Jan. 24, 1957, Ser. No. 636,173

4 Claims. (Cl. 46—149)

This invention relates to animation simulators and the principal object of the invention is the provision of an amusement device in which live or naturally moving objects such as human beings, animals, birds, insects, vehicles, etc., have their movements simulated with practical exactness.

Another object of the invention is the provision of a device of this character in which the customary visible center post, which propels the figurine, is entirely eliminated and the motive power for moving the figurine is applied directly and invisibly to each leg thereof, incidentally more accurately simulating the act of walking.

A still further object of the invention is the provision of means within the figurine itself for maintaining it constantly in a vertical position even without any direct means of support from the propelling mechanism.

A still further object of the invention is the provision of mechanism which will impart directly to the legs of the figurine a natural alternating forward step by step motion free from jerks, yet giving the body of the figurine an unvarying uniform and continuous forward motion as in walking.

And a still further object of the invention is the provision of means for supporting the floors between the moving walkways made necessary by the rotary or elliptical runways over which the figurines are caused to travel.

And a still further but important object of the invention is the provision of means for translating simple rotary motion as delivered to the device, into uniform step by step alternating forward motion with automatic braking means during the stop intervals.

Other and further objects will appear in the specifications and be specifically pointed out in the appended claims, reference being had to the accompanying drawings exemplifying the invention and in which:

Fig. 1 is a top view of the device taken on the line 1—1 of Fig. 2.

Fig. 2 is a vertical section on the line 2—2 of Fig. 1.

Fig. 3 is a vertical section on the line 3—3 of Fig. 4.

Fig. 4 is a vertical section on the line 4—4 of Fig. 3.

Fig. 5 is a diagrammatic view of the gears used in translating rotary motion into uniform step by step forward motion.

Referring to the drawings in which like characters and numerals of reference refer to similar parts throughout the several views, the numeral A9 denotes an open box housing and having on its inner bottom a centrally disposed boss A10 which serves as a thrust bearing for the lower end of the vertical shaft A11, the upper end of said shaft terminating level with the upper side of the box A9 and where it is journaled in the stationary centrally disposed disc A12. Attached to the shaft A11, as by a press-fit, is the pan-shaped disc 13, the upper annular flange of which is turned inwardly at 14, forming a circular runway for attaching figurines around the circumference of the flange 14 are equally spaced holes 15L, there being a narrow clearance space 16 between the flange

2

14 and the stationary disc A12 and another similar clearance 17 between the flange 14 and its associated encompassing disc 18 which has its flange 36 turned outwardly as illustrated and which also has an equal number of spaced holes 15R around its circumference. The disc 18 is press-fitted to the hollow shaft 19, this shaft acting as a bearing for central shaft A11 as illustrated in Fig. 2.

To the lower ends of shafts A11 and 19 are press fitted the gears 22 and 23 respectively, which gears mesh with the pinions 20 and 21 respectively, both of said pinions being press-fitted to the common shaft 24 and therefore rotating in the same direction as one, as better illustrated in Figs. 2 and 5. The shaft 24 has a bevel gear 25 press-fitted thereto which in turn is rotated by the bevel gear 26 and which latter is press-fitted to shaft 27 and which shaft rotates by means of the crank 28 and handle 29 as will be readily understood. Of course it is apparent that instead of the manual operation of turning crank handle 29, an electric motor may be substituted.

20 Referring now again to Fig. 1, the flanges 14 and 36 are presumed to rotate in the direction of arrow 31 although by reversing the direction of crank handle 29, flanges or platforms will revolve in the opposite direction. However, arranged to be removably fitted into the holes 15L and 15R is a figurine having the depending pins 32L and 32R respectively, see Figs. 3 and 4, which pins are pivotally attached together with the shoes 33L and 33R and lower ends of the legs 58L and 58R respectively. There is no standard or vertical center post necessary to hold this figurine in erect position and it is "walked" along the roadway composed by flanges 14 and 36, solely by the alternate forward movements of the legs. Consequently, the pan-shaped discs 13 and 18 must rotate in the same direction but as one disc is rotating the other disc is stopped or dwells for an equal period of time, and so on continually. This alternating forward motion is attained by means of the gearing illustrated diagrammatically in Fig. 5, wherein the crank handle 29 is turned in the direction of arrow 36, both pinions 20 and 21 being attached to the same shaft 24, rotate together in the direction of arrow 37 and their meshing gears 22 and 23 respectively, in the direction of arrows 38, but while gear 22 is rotating, having at that time its teeth in mesh with the teeth of pinion 20, the gear 23 is motionless, its teeth not being in mesh at the same time with its driving pinion 21. Instead, one of the convex surfaces 39 of the pinion 21 fits closely into one of the concave surfaces 40 between the tooth spaces on gear 23 as they are successively turned to this position, and consequently the gear 23 does not rotate but incidentally is held in braked position until the tooth 41 of pinion 21 will enter the tooth interstice 42 of gear 23 at which instant one of the convex curved parts 39 of pinion 20 engages one of the concave parts 40 of gear 22 which stops its rotation while gear 23 rotates, and so on alternating continuously. In this manner the discs 13 and 18 are alternately driven forwardly exactly simulating the leg motions of a person walking. As herein illustrated, Fig. 5, for each complete revolution of the crank handle 29, there will be two complete steps by each leg of the figurine, including dwells. If a pitman were used as an intermediary in the translation of rotary motion to rectilinear motion, as here required, no uniform speed could be attained as, during the middle portion of the movement, the rectilinear motion would be greater than at either end, thus imparting jerky motion to the legs.

60 In addition to the inner walkways 14 and 36, I also illustrate an outer walkway 95 and 96 which are the annular flanges of the pan-shaped discs 44 and 45 respectively which encircle the stationary platform 54 and have spaced holes 15L and 15R similar to flanges 14 and

70

36. The discs 44 and 45 are press-fitted to the hollow shafts 46 and 47 respectively and which are press-fitted to the gears 48 and 49 respectively. These gears mesh with pinions 50 and 51 respectively in the same manner as previously described with gears 20 and 21, but in this instance revolve in the opposite direction, namely as shown by arrow 43, thus permitting persons to "walk" in opposite directions as is natural. To attain this result, the pinions 50 and 51 are press fitted to hollow shaft 52 to which bevel gear 53 is attached and which meshes with bevel gear 26. It will thus be apparent that while shaft 24 is rotating in one direction, its encompassing hollow shaft 52 revolves in the opposite direction. In order to support the circular platforms 12 and 54 on a level with top of box A9, an overhead bridge or trestle 55 spans the entire width of the box as illustrated, the screws 56 securing the bridge piers to the platforms. Arches 57 are thus provided for the figurines to pass through, the bridge 55 being easily disguised to represent mountains, buildings, etc. It will thus be apparent that I have provided a method of using a plurality of walkways, one within the other, in a natural setting.

The figurine may depict any walking or moving object such as a human being, lion, horse, chicken, caterpillar, or even an object on wheels or a hopping animal such as a kangaroo or rabbit as will be described later. In Figs. 3 and 4 a man figurine is illustrated wherein the pins 32 are pivotally attached to the shoes 33 together with the lower leg members 58L and 58R and these are pivoted at the knees at 71 to the upper leg members 60L and 60R, the upper leg members being pivoted together within the lower part of the body 35 at 61. Lazy-tong members 62 are pivoted at 63 to the upper leg member extensions and to themselves by shaft 64, the protruding ends of which shaft are confined at either inner side of the body 35 by the vertical slots 66. It will thus be apparent that both legs act in unison, if one leg moves forward the other leg will move correspondingly and relatively rearwards. Furthermore, no standard or prop is required for securing the body 35 in an upright position and alternating forward motion need be applied to the feet only to simulate a man walking, all mechanism being totally concealed from the viewer.

Between the shafts 61 and 64 and the lower and upper ends of the slots 66 are located small springs 67. These function to equalize and diminish the "bobbing" of the head and body 34 and 35 which occurs naturally when a person is walking because, as one leg passes the other leg, both legs momentarily assume a vertical position as will be readily understood. However, in actual walking by a person, the knees and hip joints "take up" a small amount of this bobbing and to counteract this effect in a figurine, the springs 67 will be compressed from both directions as the legs assume a vertical position, this reducing the bobbing practically in half, as will be readily understood. By using the spring 67 only at the bottom of the slot 66, there will be no bobbing. It will be noted that the holes 15L and 15R are in equally staggered relation in respect to the flanges 14 and 36.

The lazy-tong arms 62 are upwardly extended a short distance past the pivot point 64. This extension has the function of striking the lower ends of the arm levers 68 so that, as the legs move more vertically, the shaft 64 will also rise a short distance against the tension of springs 67, thus enabling the ends of the lazy-tong levers 62 to strike the lower ends of the arm levers 68 and thus move the arms 69 as in walking, the arm 69 and lever 68 being solidly attached to their respective shafts 70. The lower legs 58L and 58R can be bent slightly backwards at the knees at joint 71 as in actual walking. This is accomplished by means of the flat spring 72 attached at its lower end to the lower legs 58 at the rear thereof but extending upwards slightly beyond the knee joint 71 and

thus normally holding the upper and lower legs in straight alignment but yielding to a certain predetermined degree of pressure to bend the springs as shown by the dotted lines. This bending starts at the time the step 5 starts in natural simulation of walking. Another but rigid plate 73 is attached to the lower legs at the front thereof below the knee and extends upwards a similar distance as illustrated, thus preventing the lower leg from bending frontwards, an unnatural condition. The pins 10 32 which removably enter the holes 15L and 15R of the alternating rotary platforms 14 and 36 as previously mentioned, are pivoted to the shoe 33 and lower leg 58 by means of the lateral pins 74. This gives to the shoe 15 a certain looseness to adjust itself within predetermined restraining limits, not shown, to simulate actual walking. In use, the legs would be covered by cloth trousers shown by the dotted lines 75. Referring again more particularly to Figs. 1 and 5, a quarter turn of the pinion 20 with the teeth meshed would cause the figurine 35 to take the step, see Fig. 1, from the hole 76L to the hole 77L, shown by shoe, while the right shoe would be at hole 78R. The next quarter turn of pinion 20 would hold the shoe at 77L while the teeth of pinion 21 would be in mesh with gear 23 and move right shoe to hole 79R and so on. The same is true of the outer walkways 95 and 96, the shoes 80 and 81 being illustrated.

25 To prevent the shoe 33 from dragging along the walkway as the rearmost leg begins to take a forward step and naturally assumes a more vertical position and also to slightly bend the knee in a natural manner, an undulating strip 82 is provided under each runway, see Figs. 2, 3 and 4, these strips being attached as by soldering, to the undersides of the stationary platforms A12, 30 54, etc. and extend around the entire circumference directly beneath the holes 15L and 15R. Referring more particularly to Fig. 3, it will be noted that the pin 32R, which is permanently magnetized and magnetically attractive to the iron undulating strips 82, is caused to rise as the pin 32R is dragged forward, the pin 32L remaining stationary. This will cause the leg 58R to bend slightly at the knee against tension of spring 72 while leg 58L remains rigid at its knee, thus simulating natural walking. Furthermore, on account of the magnetic attraction between the pin 32R and the undulating strip 82, the pin cannot become stuck or dislodged and chattering is prevented.

35 In the actual operation of this simulating device the depending permanently magnetized pins 32R and 32L of the figurine are merely placed into any of the adjoining holes 15R and 15L respectively. The rotating means is then applied and the figurine walks over the walkway in a simulating natural manner. A four legged animal such as a horse would be provided with a pin 32 for each leg and the animal would walk on all fours as will be readily apparent. In fact, there is no limit to the variety of figurines that may be used in connection with this device, besides a complete menagerie, such figurines as caterpillars, chickens and even boats and wheeled vehicles.

40 From the foregoing description it will be apparent that I have evolved an animation simulator which will more faithfully imitate the motions of moving objects, especially legged creatures, in that the required locomotion given to the body is transmitted directly and invisibly to the feet of the creature or figurine, the two legged objects being caused to remain in natural upright position by an invisible lazy-tong mechanism within the hollow body thereof, simple rotary motion being transferred into forward alternating motion in exact simulation of walking, all with means for permitting a plurality of walkways one within the other and rotating in opposite directions if desired, together with an absolutely invisible moving platform or other propelling mechanism.

Having thus described my invention, I claim:

1. An amusement device for simulating animative walking creatures comprising two adjoining circular concentrically arranged platforms with the upper surfaces thereof in the same horizontal plane, means for imparting equal predetermined rotary movements in one direction of each of said platforms alternately, vertically positioned adjacent holes in the peripheries of said platforms, said holes being staggered a uniform distance apart relative to each platform, an associated walking two-legged figurine removably mounted on the upper surfaces of said platforms, each leg of said figurine terminating in a pin adapted to slidably fit into one of said vertically disposed holes in each respective platform.

2. An amusement device as in claim 1, and a magnetizable strip located underneath a portion of each platform at the line of travel of said figurine, the lower tip of aforesaid pin attached to the legs of said figurine being magnetized and adapted to contact the upper surfaces of said magnetizable strips during the intermittent rotative movements of said platforms.

3. An amusement device for simulating animative walking creatures comprising a rotatable circular horizontally disposed platform, a ring-shaped rotatable platform adjoining and encircling the said circular platform and on the same horizontal plane therewith, figurine attaching means located in staggered relation on said respective platforms, an associated two-legged figurine each foot of

which is adapted to be attached to said respective staggered attaching means on said platforms, means for imparting equal predetermined rotary movements in one direction to each of said platforms alternately, means for braking each of said platforms while the adjoining platform is in motion, a torso and head on said figurine, and a lazy-tong mechanism of which the legs of said figurine are a part for keeping the torso in constant upright position while said figurine is "walking" through the alternating "step by step" movements of said platforms.

4. An amusement device for simulating walking creatures comprising two adjoining rotatable platforms on the same horizontal plane, a walking figurine, means for removably attaching one foot of said figurine onto one of said rotatable platforms and the other foot to the adjoining platform, and means for applying alternating "stop and go" forward motion to said platforms.
